UNITED STATES PATENT OFFICE.

JAMES WEST, OF BROOKLYN, NEW YORK.

DESIGN FOR A FONT OF COMBINATION TYPE ORNAMENTS.

SPECIFICATION forming part of Design No. 16,920, dated September 28, 1886.

Application filed March 13, 1886. Serial No. 195,166. Term of patent 3½ years.

To all whom it may concern:

Be it known that I, JAMES WEST, of Brooklyn, county of Kings, and State of New York, have invented a new and original Design for 5 a Font of Combination Type Ornaments, of which the following is a full, clear, and exact description, reference being had to the accompanying specimen or impression, making part of this specification, which is an exact representation of my design.

This design relates to a font of combination type ornaments, as shown in the accompanying fac-simile.

The design consists in a font of type ornaments, as shown by figures 1 to 23.

1 represents surface shading; 2, meadow-grass; 3, an oarsman; 4, reeds; 5, reeds and birds; 6, a huntsman in the bulrushes; 7, a mill; 8, a surface shading; 9, grass; 10, water and grass; 11, a path and grass; 12, a gate; 13, a fence; 14, a wagon; 15, 16, 17, 18, 19, and 20, trees; 21 and 22, houses; 23, dog.

What I claim as my invention, and desire to secure by Letters Patent, is—

The design for a font of combination type 25 ornaments, substantially as herein shown and described, and consisting of the type ornaments 1 to 23, inclusive.

In testimony that I claim the foregoing as my invention I have signed it this 12th day of 30 March, 1886.

JAMES WEST.
